US00D843070S

(12) United States Design Patent (10) Patent No.: US D843,070 S
(45) Date of Patent: * Mar. 12, 2019

(54) BRIDLE

(71) Applicant: SCHOCKEMÖHLE SPORTS GMBH, Muhlen (DE)

(72) Inventor: Franz Schockemöhle, Muhlen (DE)

(73) Assignee: SCHOCKEMOHLE SPORTS GMBH, Steinfeld-Muhlen (DE)

() Term: 15 Years

(21) Appl. No.: 35/504,394

(22) Filed: Sep. 21, 2017

(80) Hague Agreement Data

Int. Filing Date: Sep. 21, 2017

Int. Reg. No.: DM/099500

Int. Reg. Date: Sep. 21, 2017

Int. Reg. Pub. Date: Feb. 9, 2018

(30) Foreign Application Priority Data

Mar. 24, 2017 (DE) 40 2017 100 360

(51) LOC (11) Cl. 30-04

(52) U.S. Cl.

USPC D30/136
